FINGER RING

Bernard I. Mechanic, 2425 Oakton St.,
Evanston, Ill. 60202

Filed Oct. 18, 1971, Ser. No. 190,440

Term of patent 14 years

Int. Cl. D11—01

U.S. Cl. D45—10 C

FIG. 1 is a front view of a finger ring according to the invention;

FIG. 2 is a side elevational view of the finger ring shown in FIG. 1;

FIG. 3 is a right side elevational view of the finger ring shown in FIG. 1;

FIG. 4 is a top view of the finger ring shown in FIG. 1; and

FIG. 5 is a bottom view of the finger ring shown in FIG. 1.

I claim:

The ornamental design for a finger ring, as shown.
